Application February 14, 1947, Serial No. 728,419

13 Claims. (Cl. 57—100)

1

The present invention relates to driving devices for high speed yarn spindles.

The invention is concerned specifically with the provision of a novel and improved spindle drive for use in machines adapted for yarn spinning, twisting, winding and like operations, such machines being constructed with relatively large numbers of such yarn package carrying spindles arranged in two parallel rows, and with a power drive usually in belt form which is geared and operated to rotate the spindles at a maximum speed of about ten thousand revolutions per minute. Applicant has found that when the speed of rotation of the spindles is roughly doubled to a rotational speed of twenty thousand revolutions per minute, a substantial improvement is noticeable in the yarn handling qualities of the machine apart from the obvious advantage of increased production. At the higher speed, a firmer yarn balloon is formed which is less subject to fluctuation in size than is the case where the spindles are driven at the lower conventional rate. A noticeable reduction in the number of breaks occurring in the yarn feed is observed particularly for the handling of synthetic yarns of fine count.

Considerable difficulty has been experienced in providing a spindle drive which is capable of continuous operation to drive the spindles at the greatly increased rates. Attempts to increase the speed of the conventional belt drives for rotating yarn twisting spindles substantially above levels currently employed have been unsuccessful. Further increase in the already high linear rate of feed of driving belts has been found to lead to rapid deterioration and breakage of belts, the loads imposed on the bearing surfaces tend to become excessive, and serious vibration faults appear which seriously interfere with the feed of the yarn, and also lead to damage to the operating parts of the machine. The use of separate electric motors for driving the individual spindles has not provided a satisfactory solution to the problem presented.

It is a principal object of the invention to provide in a yarn processing machine of the general character described, novel driving devices capable of driving a multiplicity of yarn twisting spindles continuously and efficiently at substantially increased speeds in the order of twenty thousand revolutions per minute.

More specifically, it is an object of the invention to provide spindle driving devices including a driver of such form and a multiplicity of yarn spindles so grouped with relation to the driver to cause the lightly constructed and delicately

2

mounted yarn twisting spindles to be driven at speeds in the order of twenty thousand revolutions and upward per minute without setting up excessive strains or stresses or causing excessive vibration in either the driving or driven parts of the machine.

It is a further object of the invention to provide a novel and improved means for the transmission of power from a main driver to effect the rotation of the lightly constructed and delicately mounted yarn twisting spindles at the extremely high rotational speeds herein contemplated, and without subjecting either the driving or driven elements of the machine to excessive vibration or strain.

In carrying out the invention, a novel construction and arrangement of the yarn twisting spindles and of the driving connections therefor is provided in a yarn processing machine, which 20 consists in the provision of a rotary yarn spindle driver, a series of yarn twisting spindles grouped in circular relation contiguous to the periphery of the driver to be driven therefrom, and means to establish a driving relation between the driver and each of the spindles.

In the preferred form of the invention illustrated, the machine is entirely supported from a central vertically arranged column on which are carried a circular ring support having series of 30 yarn twisting spindles and bearings for the hub of the rotary yarn spindle driver. A driver having a driving periphery in the order of three to five feet in diameter, has been found to be of advantage to provide a most efficient operating 35 connection between the driver and individual spindles. Further in order to utilize most effectively the advantages of compactness and efficiency inherent in the disclosed construction, it is proposed to employ two or three tiers of yarn 40 spindles together with a yarn spindle driver for each tier, which will be carried one above the other on the central column. For clarity of illustration and to avoid unnecessary duplication, one tier of spindles only together with its driver is 45 shown in the drawings.

Further in accordance with the invention, the means to establish a driving connection between the driver and each of the spindles, takes the form of a magnetic field consisting of a series of 50 high density flux areas spaced from one another about the peripheral driving edge of the driver to produce a rapidly moving field of fluctuating strength, and armature elements which take the form of disk members supported to turn with 55 the respective spindles, and are further con-

structed and arranged to be responsive to and to be rotated at a very high rate by the action of the rotating field.

In accordance with the invention, a very simple construction and arrangement of the field and armature elements of the drive has been developed, of which the field element consists of a ring wound electro-magnet and pole elements in the form of peripherally disposed plates of opposite polarity, and with serrated edges to produce a series of high density flux areas extending across the peripheral edge of the driver. The armature elements associated with the driven spindles consist of a series of disk members which are supported to turn with the spindles, and to project into the path of movement of the high density flux areas to be driven thereby. The disk elements are preferably formed with synchronizing poles which are in spaced relation to the high density flux areas of the driver to cause the spindles to be driven at a speed which is in a definite ratio to the speed of rotation of the driver.

In a preferred form of the invention, the driven disk members may be constructed of any light electricity conducting material such as aluminum, so that the disks tend to be rotated by the rapidly rotating fluctuating field of the driver by the force of induction, and disks or spots of any easily magnetized material such as soft iron are provided in the disks to serve as synchronizing poles. The induction drive produced in this manner is well adapted to permit any individual spindle to be stopped and again started during the continued rotation of the driver and remaining spindles of the machine, the individual spindle with its disk being rapidly brought up to speed and then locked in synchronized driving relation to the driver in the manner of any synchronous induction motor.

With the above stated and other objects in view as may hereinafter appear, the several features of the invention consist also in the devices, combinations and arrangement of parts herein-after described and claimed, which together with the advantages to be obtained thereby will be readily understood by one skilled in the art from the following description taken in connection with the accompanying drawings, in which Fig. 1 is a cross sectional view in elevation of a yarn processing machine embodying the several features of the invention, and showing particularly the frame, the driving assembly and a pair of yarn spindles and spools arranged to be driven thereby; Fig. 2 is a fragmentary sectional view on an enlarged scale showing particularly the arrangement of the electro-magnetic driving disks and the spindle supported driven disk element cooperating therewith; Fig. 3 is a fragmentary sectional view on an enlarged scale of parts shown in Fig. 1, to illustrate particularly the arrangement of the electrical contactors and collector rings for the electro-magnet windings in the driver; Fig. 4 is a plan view of the machine shown in Fig. 1; Fig. 5 is a fragmentary sectional view on a greatly enlarged scale of the driver and spindle driven thereby as shown in Figs. 1 and 2, and with the added illustration of a spindle brake; and Fig. 6 is a fragmentary plan view on the same scale and illustrating substantially the parts shown in Fig. 5.

The yarn processing machine herein disclosed as embodying in a preferred form the several features of the invention, comprises a base 10 on which is rigidly mounted a vertically extending

column 12. The rigid supporting structure of the machine also includes a spindle supporting ring 14 which is mounted on five arms 16 which are secured to and extend outwardly from the column 12. Each of the arms 16 is provided at its outer end with a vertically extending screw-threaded bolt 17 which is secured at its upper end to the ring 14 and is adjustable axially in the arm 16 by means of check nuts 18 to permit a ready adjustment of the vertical position of the spindle supporting rings 14.

The spindle driving mechanism of the machine comprises generally a rotary disk-shaped driver of large diameter consisting of a disk 20 which is carried on the outwardly extending flange 22 of a vertically arranged hub member 24 rotatably supported on the column 12 by means of upper and lower ball bearings 26 and 28. An L-shaped collar 30 located beneath the hub 24 and lower bearing 28 on column 12 is adapted to provide vertical support for the driver. The driver 20 is arranged to be driven from an electric motor 32 suspended from a bracket 34 in the base 10 through connections which include a vertically arranged drive shaft 36 which extends upwardly within the column 12, being supported in an upper bearing 38 and lower bearing 40, and connected by means of a coupling 42 with the armature shaft 44 of the motor 32. At its upper end the shaft 36 has secured thereto a gear 46 which meshes with an internally toothed gear ring 48 rigidly secured to the hub 24 of driver 20.

In the illustrated construction, the ring 14 provides support for a series of fifty yarn twisting spindles which are preferably, although not necessarily, constructed and arranged in accordance with the illustration of my copending application Serial No. 708,170, filed November 6, 1946, for Yarn spindles, and are well adapted for continuous operation at rotational speeds of twenty thousand revolutions and upward per minute. Each individual spindle as best shown in Fig. 5 of the drawings, comprises a vertically arranged blade 50 which is supported in appropriate bearings within a cylindrical housing having a supporting flange formed thereon as indicated at 51 in Fig. 5. A cylindrical sleeve or skirt 52 which is secured at its upper end to a collar 54 on the blade 50 extends downwardly over and covers that portion of the housing located above the supporting flange 51. A portion of the housing located below the flange 51 (not shown) extends downwardly through an aperture in the supporting ring 14, and has mounted on the lower end thereof a lubricant reservoir 58. The spindle is held in place by the engagement of the flange or shoulder 51 of the housing with the upper side of the ring 14 and a clamping nut 60 screw-threaded to the lower portion of the housing and arranged for pressing engagement against the under side of the supporting ring 14.

Each spindle is provided with means for mechanically braking the spindle to stop, which comprises (see Figs. 5 and 6) a braking lever 62 provided with a friction face 64 adapted for engagement with the cylindrical sleeve or skirt 52 of the spindle. The braking lever 62 is supported on a pin 66 carried in a bracket 63 mounted on the upper side of the supporting ring 14, being spring-pressed by means of springs 70 in a clockwise direction from the position shown in Fig. 5 against the spindle. The braking lever 62 is normally maintained in inoperative position by means of a latch 72 mounted on a pivot pin 74 in a bracket 76 secured to the under side of the

supporting ring 14. A compression spring 18 acts on the latch lever 72 to maintain the same in the latching position shown in Fig. 5.

An important feature of the invention consists in the provision of means for transferring a driving impulse from the peripheral edge of the driver travelling at very high peripheral speeds at a linear rate in the order of two miles per minute to a series of lightly constructed and delicately balanced yarn twisting spindles supported adjacent to and about the periphery of the driver. In the preferred form of the invention, this driving impulse is produced by a rapidly moving fluctuating magnetic field which is set up across the peripheral driving edge of the driver, and is arranged to act upon cooperating driven disks in the nature of armature elements associated with the individual spindles.

As will be evident from a consideration of the drawing, the driver 20 takes the form of a steel disk having secured thereto a ring 82 which is of non-magnetic material preferably aluminum. The ring 82 in turn provides support for a series of upper and lower outwardly projecting ring segments 84 and 86 which form oppositely polarized pole pieces for a ring-shaped electro-magnet extending entirely around the peripheral edge of the driver. The electro-magnet is formed with an iron ring or core 88 fastened between the segmental plates 84 and 86 abutting the ring support 82, a ring coil 90 which is disposed between the plates 84, 86 against the iron core 88, and a series of spacing segments 92 interposed between the plates toward the outer diameter of the driver. The pole plates 84, 86 as best shown in Fig. 6, are formed with scalloped edges to provide outwardly projecting pairs of poles 89 which produce separated flux areas of high density extending across the driving edge of the driver at spaced intervals about the periphery thereof. The air gap between the poles of the pairs is narrowed by means of additional pole pieces in the form of steel plates 94, 96.

Power for the ring electro-magnet coil 90 is readily supplied by means of appropriate leads, ring conductors and brushes carried respectively by the driver and supporting column 12 of the machine. The magnet coil leads are indicated at 98 and 100 (see Fig. 1), being connected with two slip rings 102 and 104 carried by the upper end of the driver hub 24. The slip rings are engaged respectively by brushes 106 and 108 yieldably supported in holders 110 and 112 on a bracket 114 on the column 12. The lead wires for the brushes are indicated respectively at 116 and 118 in Fig. 3.

As shown in the drawings, each of the yarn twisting spindles 50 has mounted to turn therewith a disk element 120 preferably of aluminum, although any electricity conducting material may be employed. These disks are arranged to project between the pole plates 84, 86. The rotation of the driver 20 causes the high density flux areas extending between the pairs of poles 89 to be passed in very rapid succession across the disks to produce the effect upon each successive magnetic disk of a rapidly fluctuating magnetic field, causing the disks to rotate. The operation of the driving connection in this respect may be compared with the operation of a watt meter of standard type in which the relative movement of an aluminum disk through a magnetic field is employed to produce a slight drag upon the movement of the disk.

Circular insets 122 forming spots of magnetic material are provided in each of the disks 120 adjacent the peripheral edge thereof, and are spaced

from one another about the disk in such angular relationship to cause them to be synchronized with the projecting pairs of poles 89 of the driver. In the preferred form of the invention illustrated, the magnetic insets 122 are of soft iron to provide synchronizing poles which will tend to cause the disks to rotate in a substantially synchronized relation to the driver.

The driving impulse provided by the magnetic field and armature elements above described, has been found sufficiently powerful to drive the spindles at the high speed of rotation required, has been found to impose no discernible strain on the spindle bearings, to operate substantially without friction or power losses and without any heating of the driving connections, and with such flexibility as to permit the individual spindles to be readily stopped upon the application of a light braking pressure thereto for replenishment, replacement or repair. Upon release of the brake, any spindle stopped in this manner will again start to rotate, and is very quickly brought up to full speed.

The manner in which the drive operates may be briefly described as follows. Excitation is applied to the electro-magnet carried by the driver from a constant source of current, preferably D. C., so that a powerful magnetic field is created consisting of a series of high density flux areas extending across the peripheral edge of the driver between the pairs of poles 89. The rotation of the driver causes the high density flux areas to be traversed across the disks 120 in rapid sequence. A fluctuating field is thus produced, the fluctuations being at a very high frequency which is the product of the number of revolutions per minute of the driver times the number of pairs of poles disposed about the periphery of the driver. This rapidly fluctuating field serves to produce a substantial drag upon the disks 120, tending to cause these to rotate. The soft iron insets 122 above referred to, are acted upon in a similar manner by the fluctuating field, producing a magnetic reaction in the insets which fluctuates rapidly in response to the fluctuations of the moving field.

The magnetic insets employed in this manner may be regarded as in the nature of synchronizing poles which cause the spindles to rotate substantially in synchronism with the driver.

In accordance with the invention, it is contemplated that permanent magnet insets of a magnet material having a high degree of retentivity may be employed, if so desired, to provide a driving impulse based directly upon magnetic attraction.

It will be noted that in order to reduce hysteresis to a minimum, the serrations between the poles are so formed as to cause the circumferential center distance between individual poles to be substantially equal to the distance from the base to the tip of the individual poles formed by these serrations.

In the operation of the machine, the motor 32 acting through armature 44, extension shaft 36 and gears 46, 48, rotates the driving disk 20 at a predetermined speed which may be approximately 800 R. P. M. Since there are twenty segmental pole plates 84, 86, each with five individual serrations with pole extensions 94, 96, making a total of one hundred areas of high flux density extending across the peripheral edge of the driver 20, and these are in turn synchronized with four magnetic insets or plugs 122 in the disks 120 on the spindles, it follows that one revolution of the driver 20 will cause each spindle to be rotated

through twenty-five or substantially twenty-five revolutions subject to some allowance for slippage, or in the neighborhood of twenty thousand R. P. M. for a rotational speed of the driver of 800 R. P. M.

It will be understood that those features of construction and arrangement of the yarn processing machine herein described relating particularly to the use of a driver of large diameter and the arrangement of the driven yarn spindles in circular relation contiguous to the peripheral driving edge of the driver, are not limited in their application to a spindle driving assembly in which the driving connection between the driver and spindles is provided by the action of a pulsating magnetic field extending across the peripheral edge of the driver upon cooperating armature elements carried by the respective spindles. With any form of magnetic or equivalent driving connection, the use of a centrally located driver having a driving peripheral edge of substantial diameter in the order of three to five feet, is of great advantage to permit the rotation of the driver at a relatively slow rate in the order of 800 R. P. M., while maintaining a linear peripheral speed sufficient to drive the spindles at twenty thousand revolutions or more per minute. A very compact and efficient arrangement of the machine providing for a maximum number of spindles is made possible with the illustrated construction. When a driver of sixty inches is employed, fifty spindles can be mounted about the periphery thereof with sufficient spacing therebetween to prevent possible interference with the ballooning of the yarn drawn from packages on the spindles. The use of a driver having a peripheral driving edge of substantial diameter has been found to be of advantage further in that the moving surface which acts upon and rotates each individual spindle, moves in a relatively straight line, thus providing a driving contact of maximum efficiency whether a magnet and armature or other driving connection is employed. A driver of substantial diameter having a peripheral edge sixty inches in diameter and rotating at the rate of 800 R. P. M., has the specific advantage that it permits the use of armature disks associated with the spindles which are also of relatively large diameter in the order to four inches to provide a relatively powerful driving torque tending to rotate the individual spindle.

The arrangement of the machine with a central column from which the ring support for the spindles and the driver are supported, makes for efficiency in that all external supporting structure is eliminated which would tend to obstruct the work of the machine attendant and must reduce substantially the number of spindles it would be possible to locate about the driver. It will be understood that the invention contemplates also the provision of a machine of this general description in which a plurality of tiers or banks of spindles are supported one above the other from the central column, together with the associated drivers and the usual yarn collecting or spooling devices common to yarn processing machines of this general type.

It will be understood that the invention is not limited to the specific embodiment shown, and that various deviations may be made therefrom without departing from the spirit and scope of the appended claims.

What is claimed is:

1. A yarn spindle driving assembly, which

comprises a frame, a yarn spindle driver arranged to turn on a vertical axis and having a driving perimeter of substantial diameter, a series of vertically arranged yarn spindles

5 mounted on the frame in circular relation contiguous to said driving perimeter, a driving connection between said driving perimeter and the spindles comprising armature disks on the spindles, and means to produce a magnetic field in said driving perimeter passing through said disks, and power means for rotating the driver.

10 2. A driving mechanism for yarn spindles, which comprises a frame, a yarn spindle driver having a driving periphery of substantial diameter, a series of yarn spindles located in circular relation about the peripheral edge of said yarn spindle driver, driven disk elements on said spindles, said driver and disks providing cooperating magnetic field producing means and armature means whereby rotation of the driver is effective to rotate the disks, and power means for rotating the driver.

15 3. A yarn spindle driving assembly, which comprises a frame, a yarn spindle driver having magnetic means to produce a series of high density flux areas spaced from one another about the peripheral edge of the driver, a series of vertically arranged yarn spindles supported on the frame in circular relation contiguous to said peripheral edge, a disk mounted on each spindle within the influence of said magnetic flux areas, synchronizing poles spaced from one another about each disk to cooperate with said high density flux areas whereby rotation of the driver is effective to produce a synchronized rotation of the driver and spindles, and means for rotating the driver.

20 4. A yarn spindle driving assembly, which comprises a frame, a yarn spindle driver arranged to turn on a vertical axis and having a driving perimeter of substantial diameter, a series of vertically arranged yarn spindles mounted on the frame in circular relation contiguous to said driving perimeter, and means for driving the spindles from the driver at a synchronized rate, comprising a magnetic field producing means providing pairs of separated poles spaced from one another about the peripheral edge of the driver, disks of non-magnetic electrical conducting material secured on said spindles to be passed between the poles of said pairs, and spots of magnetic material spaced about said disks to provide synchronizing poles whereby rotation of the driver is effective to effect a synchronized rotational movement of said disks and spindles therewith.

25 5. A yarn spindle driving assembly, which comprises a frame, a yarn spindle driver arranged to turn on a vertical axis and having a driving perimeter of substantial diameter, a series of vertically arranged yarn spindles mounted on the frame in circular relation contiguous to said driving perimeter, and a driving connection between the driver and spindles in the form of an electromagnet on the driver having upper and lower pole plates with pairs of polar extensions extending radially outwardly of the driver at spaced intervals about the periphery thereof, disks of non-magnetic electrical conducting material projecting between the polar extensions of the pairs, and means for rotating the driver.

30 6. A yarn spindle driving assembly, which comprises a frame, a yarn spindle driver arranged to turn on a vertical axis and having a driving perimeter of substantial diameter, a series of vertically arranged yarn spindles mounted on the frame in circular relation contiguous to said driv-

ing perimeter, and a driving connection between the driver and spindles in the form of an electro-magnet on the driver having upper and lower pole plates with pairs of polar extensions extending radially outwardly of the driver at spaced intervals about the periphery thereof, armature disks having synchronizing poles mounted on said spindles to project between the polar extensions of the pairs, and means for rotating the driver.

7. A yarn processing machine, which comprises a base, a column, a driver rotatably mounted on the column and having a driving periphery of substantial diameter, a ring support carried from the column, a series of yarn spindles on the ring support located in circular relation contiguous to said driving perimeter, means to establish a driving relation between the driving perimeter of the driver and each of said spindles, and power means for rotating the driver.

8. A yarn processing machine, which comprises a base, a vertically arranged cylindrical column, a driver rotatably supported on the column and having a driving perimeter of substantial diameter, a ring support carried from the column, a series of yarn spindles located in circular relation on the ring support contiguous to said driving perimeter, means to establish a magnetic field about said driving perimeter, armature disks on the spindles supported within the influence of said magnetic field, and power means for rotating the driver.

9. A yarn processing machine, which comprises a base, a column, a driver comprising a driving hub rotatably supported on the column, a disk driving member carried by the hub, a ring magnet supported from the disk member having upper and lower pole plates with serrated edges providing a series of pole pairs spaced about the periphery of the driver, a stationary ring support carried by the column, a series of yarn spindles mounted in circular relation on the ring support contiguous to the driver, armature disks on the spindles projecting between the poles of said pairs, and power means connected with said hub for rotating the driver.

10. In a yarn processing machine having a rotary driver with a driving peripheral edge of substantial diameter, and a series of yarn spindles located in circular relation contiguous to the driving edge to be driven therefrom, of which the driver comprises a rotatable driving hub, a disk driving member carried by the hub, a ring magnet having upper and lower pole plates with serrated edges providing a series of pole pairs spaced about the periphery of the driver, and said spindles having mounted thereon armature disks arranged to project between the poles of said pairs.

11. In a yarn processing machine, a base, a

column, a driver comprising a driving hub rotatably supported on the column, a disk driving member carried by the hub, a ring magnet supported from the disk member, upper and lower segmental pole plates for said magnet having polar projections providing pole pairs at spaced intervals about the peripheral edge of the driver, a stationary spindle support, a series of yarn spindles mounted in circular relation on said spindle support contiguous to the driver, armature disks having synchronizing poles mounted on the spindles to project between the poles of said pairs, and power means connected with said hub for rotating the driver.

12. In a yarn processing machine, a base, a column, a driver comprising a driving hub rotatably supported on the column, a disk driving member carried by the hub, magnetic means supported from the disk member having upper and lower pole plates with polar extensions providing at spaced intervals about the peripheral edge of the driver pairs of polar extensions, a ring support carried by the column, a series of yarn spindles mounted in circular relation on the ring support contiguous to the driver, armature disks having synchronizing poles mounted on the spindles to project between the poles of said pairs, an electric motor, and driving connections located within the column connected with said hub for rotating the driver.

13. In a yarn processing machine, a rotary driver comprising a disk member, magnetic means supported from the disk member having upper and lower pole plates with serrated edges providing at spaced intervals about the peripheral edge of the driver, pairs of polar extensions each of a length substantially equal to the width of the space separating adjacent extensions, a series of yarn spindles mounted in circular relation about the peripheral edge of the driver, and armature disks on the spindles projecting between the poles of said pairs.
